UNITED STATES PATENT OFFICE.

EDWARD F. SHELLABERGER, OF DEKALB, ILLINOIS.

WIRE FENCE.

SPECIFICATION forming part of Letters Patent No. 790,597, dated May 23, 1905.

Application filed January 30, 1905. Serial No. 243,328.

To all whom it may concern:

Be it known that I, EDWARD F. SHELLABERGER, a citizen of the United States, residing at Dekalb, in the county of Dekalb and State of Illinois, have invented certain new and useful Improvements in Wire Fences, of which the following is a specification.

The object of the present invention is to provide a wire-fence fabric formed of single strands of wire and so constructed that short lengths of wire may, if preferred, be utilized to form transverse stay-wires or pickets.

A further object of the invention is to provide a construction which may be cheaply and rapidly manufactured by the use of comparatively simple mechanism.

A further object of the invention is to provide a form of knot which provides projecting ends which may be utilized as barbs, if desired.

To the above ends the invention consists in the matters hereinafter described, and more particularly pointed out in the appended claims.

In the drawings, Figure 1 is a plan view of a section of fabric embodying one form of the invention. Fig. 2 shows the intersecting portions of one of the knots in the first stage of formation. Fig. 3 shows the same in the second stage. Fig. 4 shows the finished knot. Figs. 5, 6, and 7 correspond, respectively, to Figs. 2, 3, and 4 and show a modified construction.

In making the fabric of my invention I provide a machine by means of which a plurality of longitudinal wires 1 are supported in parallel relation at a definite distance apart and by means of suitable mechanism form in said longitudinal wires at laterally opposite points open coils or loops 2. These loops are each formed of a single turn of the wire, as shown clearly in Fig. 2. In making the construction of Figs. 1 to 4, inclusive, I insert short sections of wire 3 3' through these loops to form the cross - stays, each section being slightly longer than the distance between the

longitudinal wires, so that its ends project through the corresponding open coils to a short distance, as best seen in Fig. 2. I then by means of a suitable tool or machine wrap the projecting ends around the crossing or overlapping portions 4 of the coils 2, and in thus wrapping the ends I may leave the extremities 5 projecting oppositely in the plane of the finished fabric, as shown in Fig. 3. After the ends of the stay-wires have been thus united to the coils of the longitudinal wires the latter are drawn taut and with sufficient force to draw down the loops 2 so that they snugly embrace the intertwined portions 6 of the stay-wires and form compact knots, as shown clearly in Fig. 4.

In the modification shown in Fig. 5 the pickets or cross-wires are formed of single pieces extending the full width of the fabric instead of short lengths. In this construction each cross-wire is provided at its point of intersection with its longitudinal wires with a double-returned or S-shaped bend, forming two portions 6 6', and the cross-wires are so adjusted to the longitudinal wires that the portion 4 of each coil 2 lies in the end of one of the bends, as 6, while the other projects within and through the coil. The projecting portions 6' are then severally wrapped around the overlapping portions of the coils 2, as shown in Fig. 6, and the longitudinal wires subsequently drawn down taut, so as to close the loops and form the knots approximately as shown in Fig. 7.

I claim as my invention—

1. A wire-fence fabric comprising a plurality of longitudinal wires and a plurality of cross-wires, the longitudinal wires being provided at the points of intersection with the cross-wires with loops each formed by a single turn or coil of the wire, and the cross-wires at the points of intersection being passed through the loops of the longitudinal wires and coiled outwardly around the latter.

2. A wire-fence fabric comprising a plurality of longitudinal wires and a plurality of

cross-wires, the longitudinal wires being provided at the points of intersection with the cross-wires with loops each formed by a single turn or coil of the wire, and the cross-wires at the points of intersection being passed through the loops of the longitudinal wires and coiled outwardly around the latter at the

points where the oppositely-extending portions of the longitudinal wires overlap each other.

EDWARD F. SHELLABERGER.
